TYPEWRITER STAND

Arvine N. Thomas, Canton, Ohio, assignor to
James P. Ward, Jr., Chicago, Ill.

Application June 14, 1937, Serial No. 148,198

6 Claims. (Cl. 311—1)

This invention relates to certain new and useful improvements in typewriter stands.

The primary object of the invention is to provide a typewriter stand of the knock-down type wherein different sections or units that are shipped in collapsed condition may be readily assembled by unskilled labor with the assembled sections or units presenting a rigid table or stand construction for the purposes intended.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a perspective view of a knock-down typewriter stand constructed in accordance with the present invention with the slide shelf carried thereby in extended position;

Figure 2 is a fragmentary perspective view partly in section of the inner side of a rear corner portion of the table or stand showing the connection between the side and end aprons and the upper ends of a leg;

Figure 3 is a cross-sectional view of the table with the legs broken away and illustrating the side aprons with the guides carried thereby for the sliding shelf;

Figure 4 is a fragmentary perspective view, partly broken away and shown in section;

Figure 5 is a perspective view showing the front and rear leg frames connected by a foot board;

Figure 6 is a fragmentary perspective view of the upper end of one of the front corner legs;

Figure 7 is a fragmentary perspective view, partly in section of a front corner leg and the connected side and end aprons; and

Figure 8 is a perspective view of one of the side aprons carrying the guide for the sliding shelf.

Referring more in detail to the accompanying drawings, the knock-down typewriter stand or table is formed of sections including front and rear leg assemblies, 10 and 11, a connecting foot board 12, side aprons 13, a table top 14 and a sliding shelf 15, each of the foregoing knock-down parts being assembled into stand or table formation as shown in Figure 1.

The front leg assembly 10 is formed of corner legs of angle iron construction having front flanges 16 and side flanges 17, the upper ends of the front corner legs being connected together by means of an angle iron apron strip 18 that has opposite ends thereof spot welded as at 19 to the inner sides of the upper ends of the leg flanges

16 as shown in Figures 5 and 7. The lower ends of the front corner legs are further connected together by angle iron cross-strips 20 that have their ends spot welded as at 21 to the flanges 16 and 17 of the front corner legs and as shown in Figures 1 and 5, the lower ends of the legs are suitably fashioned into feet 22 that carry gliders or the like, casters 23 being shown in Figure 1, while skids 24 are shown in Figure 5.

The rear leg assembly 11 is similar in construction to the front leg assembly and includes corner legs formed of angle iron with rear flanges 25 and side flanges 26, an apron strip 27 being secured to the inner sides of the upper ends of the rear flanges 25 by spot welding or the like as shown at 28 in Figs. 2 and 5, the lower ends of the rear corner legs being connected by a cross brace 29 spot welded at its ends as at 30 to said corner legs.

The front and rear leg frames are maintained in set-up condition by the foot board 12 that connects the cross braces 20 and 29, opposite ends of the foot board 12 being detachably connected to the cross-braces 20 and 29 by nut and bolt combinations 30 or the like.

The construction of side apron 13 is shown more clearly in Figs. 2, 7 and 8 and being formed of sheet metal or the like includes a relatively narrow horizontal top flange 31 that is outwardly directed from a side wall 32 that carries a relatively narrow inwardly directed flange 33 at its lower edge. An inwardly directed channel 34 extends longitudinally of the side wall 32 intermediate the upper and lower edges thereof and secured to the inner side of the channel 34 is a guide channel 35 having upper and lower flanges 36, the guide channel being anchored to the channel 34 by spot welding as at 37. A bolt opening 38 is formed in the side wall 32 of the apron 13 adjacent each lower corner edge thereof and a spring loop or finger 39 is struck-out from the side wall 32 of the apron adjacent each upper corner edge thereof, in vertical alignment with the adjacent bolt opening 38. A cut-away portion or notch 40 is formed in the upper terminal ends of the side flanges 17 and 26 of the front and rear corner legs and a bolt opening 41 is also formed in said flanges below said notch. When

the side aprons 13 are assembled with the front and rear leg frames 10 and 11, the top flange 31 of the apron 13 rests upon the upper terminal ends of the side flanges 17 and 26 of the front and rear legs, the struck-out fingers 39 being received in the notches 40 of the legs while the openings 38 in the side aprons register with the 55

openings 41 in the legs for the passage of nut and bolt combinations 42 or other fastening devices. A tongue 43 struck from the front flanges 16 of the front corner legs in line with the guide channels 35 provide openings 44 in said leg flanges registering with the guide channels to permit sliding movement of the shelf 15 in the guide channels 35.

The table top 14 is supported upon the top flanges 31 of the side apron 13 and has depending marginal flanges 45 as clearly shown in Figures 3 and 4.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:—

1. In a knock-down typewriter stand or table, front and rear leg frames, each including vertical corner legs and horizontal cross bars connecting the legs adjacent the upper and lower ends thereof, a foot board detachably connected at its ends to the lower cross bars, side aprons detachably connected to the upper ends of the legs of each leg frame, a table top removably supported on the leg frames, and a shelf slidably mounted in the side aprons.

2. In a knock-down typewriter stand or table, front and rear leg frames, each including vertical corner legs and horizontal cross bars connecting the legs adjacent the upper and lower ends thereof, a foot board detachably connected at its ends to the lower cross bars, side aprons detachably connected to the upper ends of the legs of each leg frame, a table top removably supported on the leg frames, a shelf slidably mounted in the side aprons, means forming a separable interlocking connection between the side aprons and upper ends of the legs, including spring tongues struck out from the side aprons and the upper ends of the legs being notched to receive the tongues.

3. In a knock-down typewriter stand or table, front and rear leg frames, each including vertical corner legs and horizontal cross bars connecting the legs adjacent the upper and lower ends thereof, a foot board detachably connected at its ends to the lower cross bars, side aprons detachably connected to the upper ends of the legs of each leg frame, a table top removably supported on the leg frames, a shelf slidably mounted in the side aprons, a longitudinally extending channel iron carried by the inner side of each side apron for a guide for the sliding shelf and the upper

ends of the legs of the front leg frame being notched for clearance of the sliding shelf.

4. In a knock-down typewriter stand or table, front and rear leg frames, each including vertical corner legs and horizontal cross bars connecting the legs adjacent the upper and lower ends thereof, a foot board detachably connected at its ends to the lower cross bars, side aprons detachably connected to the upper ends of the legs of each leg frame, a table top removably supported on the leg frames, a shelf slidably mounted in the side aprons, means forming a separable interlocking connection between the side aprons and upper ends of the legs, including spring tongues struck out from the side aprons and the upper ends of the legs being notched to receive the tongue, a longitudinally extending channel iron carried by the inner side of each side apron for a guide for the sliding shelf and the upper ends of the legs of the front leg frame being notched for a clearance of the sliding shelf.

5. In a knock-down typewriter stand or table, front and rear leg frames, each including vertical corner legs and horizontal cross bars connecting the legs adjacent the upper and lower ends thereof, a foot board detachably connected at its ends to the lower cross bars, side aprons detachably connected to the upper ends of the legs of each leg frame, a table top removably supported on the leg frames, a shelf slidably mounted in the side aprons, horizontal flanges on the upper edges of the side aprons for the support of the table top, a longitudinally extending channel iron carried by the inner side of each side apron for a guide for the sliding shelf and the upper ends of the legs of the front leg frame being notched for clearance of the sliding shelf.

6. In a knock-down typewriter stand or table, front and rear leg frames, each including vertical corner legs and horizontal cross bars connecting the legs adjacent the upper and lower ends thereof, a foot board detachably connected at its ends to the lower cross bars, side aprons detachably connected to the upper ends of the legs of each leg frame, a table top removably supported on the leg frames, a shelf slidably mounted in the side aprons, means forming a separable interlocking connection between the side aprons and upper ends of the legs, horizontal flanges on the upper edges of the side aprons for the support of the table top, a longitudinally extending channel iron carried by the inner side of each side apron for a guide for the sliding shelf and the upper ends of the legs of the front leg frame being notched for clearance of the sliding shelf.

ARVINE N. THOMAS.
